UNITED STATES PATENT OFFICE

RUSSELL G. ALLEN, OF ALTON, ILLINOIS, ASSIGNOR TO OWENS-ILLINOIS GLASS COMPANY, A CORPORATION OF OHIO

CUT-OFF MECHANISM FOR GLASSWARE FORMING MACHINES

Application filed September 10, 1930. Serial No. 480,872.

The present invention relates to improvements in cut-off mechanism for glassware forming machines and more particularly to that type of cut-off adapted to be swung across the charge receiving end of a blank mold for severing mold charges in the latter and then temporarily closing the receiving opening of said mold.

In mechanism of the above character it is customary to rigidly connect a cut-off knife and holder therefor to one end of a rock shaft whose axis is parallel with the mold axis, said shaft adapted to be oscillated at regular time intervals for imparting the necessary movements to the knife. In order to obtain satisfactory operating conditions in so far as the severing of mold charges is concerned, it is essential that the cut-off knife move in a plane exactly parallel with that face of the mold in which the receiving opening is formed. In the event such conditions do not exist, clean cut-offs cannot be obtained with any degree of regularity, with the result that unsightly cut-off scars show up in the finished articles of glassware. The construction involved in commercial type machines used at the present time does not lend itself readily to adjustment for the purpose of leveling up the cut-off knife with respect to the corresponding blank mold.

An object of the present invention is the provision of novel means whereby the cut-off knife and its holder may be angularly adjusted with respect to the operating rock shaft to thereby correct any inaccurate positioning of the knife. To this end a swivel connection or universal joint is provided between the holder and rock shaft.

Other objects will be in part apparent and in part pointed out hereinafter.

In the drawings:

Fig. 1 is a sectional elevation showing the manner in which my invention may be embodied in a standard type of cut-off mechanism.

Fig. 2 is a sectional plan view taken along the line II—II of Fig. 3.

Fig. 3 is a vertical sectional elevation taken along the line III—III of Fig. 2.

Fig. 4 is a bottom plan view of the parts shown in Fig. 3.

Fig. 5 is a detail sectional elevation showing another form of connection between the knife holder and rock shaft. 55

Fig. 6 is a sectional plan view taken substantially along the line VI—VI of Fig. 5.

Fig. 7 is a sectional elevation taken substantially along the line VII—VII of Fig. 6.

Fig. 8 is a detail perspective view of the adjusting or bearing block. 60

The invention is shown in connection with a fragment of a standard mold group such as is included in an Owens type machine, said mold group including a blank mold 10 having a cavity 10^b therein and suitably supported on a dipping frame 11, both the mold and frame adapted to be reciprocated vertically at regular time intervals as a part of the mold charging operation. A frame 12 which may 65 form a part of the usual rotating mold carriage, is arranged in proximity to the upper end of the dipping frame 11 and supports the charge severing or cut-off mechanism which includes a cut-off knife 13, knife holder 14, and a rock shaft 15. The rock shaft 15 is journaled at its upper end in a bearing 16 carried by the frame 12 and near its lower end in a bearing 17. Rocking of the shaft 15 to thereby oscillate the knife 13 is obtained 70

by standard mechanism including a rack bar 18 running in mesh with a spur gear 19 or pinion, loosely mounted for axial movement on the shaft just above the upper bearing 16. The knife is operated in the usual manner 75 as described in LaFrance Patent 1,185,687, dated June 6, 1916, being alternately raised and lowered at regular time intervals by a bell crank mechanism (not shown). Adjustment of the knife vertically with respect to 80

the mold 10 to provide proper clearance between said knife and mold is obtained by manipulating an adjusting device at the upper end of the rock shaft 15, said device including a collar 20 threaded upon the shaft 15 and rotatively resting on the upper side of the pinion 19. A hand wheel 21 is operable 85 for rotating the collar 20 so that the shaft 15 may be lifted or lowered and thereby impart 90 corresponding movement to the knife 13. 100

Leveling of the knife 13 so that it moves in a plane exactly parallel with the adjacent face 10^a of the blank mold 10 is obtained by changing the angular position of the knife 13 and its holder 14 with respect to the rock shaft 15. The construction allowing such adjustment of the knife and holder comprises a swivel connection 22 or universal joint between the holder 14 and the lower end of the rock shaft 15. In the illustrated form of swivel connection the inner end of the holder 14 is provided with a crown portion 23 (Fig. 3) whose upper convex surface 24 provides a seat for the cup 25 provided at the lower end of the rock shaft 15. This cup has concave lower face 26 adapted to frictionally engage the convex surface 24. A sleeve 27 carrying the cup 25 is keyed to the lower end of the rock shaft 15 to prevent relative rotary movement of the sleeve and shaft. Relative movement between the crown portion 23 and cup 25 except during adjustment of the knife is prevented by a locking bolt 28 or screw, which carries a washer 29 having a convex upper side, firmly seated upon the lower side of the crown 23. This locking bolt or screw 28 extends through a vertical opening 30 in the crown 23 and at its upper end is threaded into an opening 31 extending axially into the rock shaft 15.

In adjusting a cut-off knife in which the mechanism is constructed as described in the foregoing, the rock shaft 15, holder 14, and cut-off knife 13 are raised by rotating the collar and hand wheel 20 and 21 respectively, until the upper surface of the knife 13 is at the same or about the same height as the lower surface 10^a of the blank mold 10. At this point the locking bolt or screw 28 is loosened to permit any independent angular movement of the knife and holder that may be necessary to level the knife and effect proper engagement between all surfaces of the knife and said lower end of the blank mold 10.

When such position of the knife and holder has been obtained, the locking bolt is again tightened to clamp the parts in adjusted position. In operation, it is desirable to provide a slight clearance between the knife and mold. After leveling the knife to suit the mold, the adjusting collar 20 can be rotated to raise or lower the knife as may be necessary to provide such clearance and bring the knife to correct cutting relation to the mold.

In Figs. 5 to 8 inclusive, I have shown another form of my invention in which multidirectional adjustment of the knife and holder with respect to the rock shaft may be obtained through a construction differing structurally to some extent from that shown in Figs. 1 to 4 inclusive. In this second form the cut-off knife 13 is removably secured to the holder 14 by a locking screw 28^a. Relatively off-set openings 29^a in the foot portion 65 of the holder 14 and knife 13 allow the use

of a "drift bar" (not shown) or other implement in removing the knife from the holder. Such a bar is simply driven downwardly through the openings so that the knife is forced out of the holder.

A sleeve 30^a forming part of the knife holder 14 is loosely fitted over the reduced lower end 15^a of the rock shaft 15 and is secured to the latter against downward movement by a locking screw 31^a which is threaded into the lower end of the shaft. A cup like washer 32 is carried by the screw 31^a and fits over the lower end of the rock shaft, said washer having its outer upper corner cut away and curved transversely of its length to provide a bearing surface 33 contacting with an upwardly tapering bearing surface 34 on a rib 35 which forms part of the sleeve 30^a. By providing the loose fit of the sleeve 30 over the lower end of the shaft 15 and the curved bearing surface 33 on the washer 32, the knife holder and knife may be rocked about the point "A" to change their angular position relative to the rock shaft.

The angular position of the knife and holder with respect to the rock shaft is determined by the setting of the set screws 36 which are threaded through openings in the sleeve 30 and have their inner ends projecting into and contacting with the bottoms of recesses 37 provided in the reduced lower end of the rock shaft. These set screws are arranged in pairs, aligned with each other, the axis of one pair being disposed in a horizontal plane extending parallel with the length of the knife 13 and knife holder 14, while the axis of other pair is arranged in the same plane with the axis of the other screws and at right angles thereto. Thus, by turning the set screws of either pair in opposite directions, the angular position of the knife and holder with respect to the rock shaft may be varied.

An adjusting or bearing block 38 is arranged between the upper end of the sleeve 30^a and a collar 39 which is keyed to the rock shaft 15. This bearing block 38, which is in a form of a ring, is provided on its lower side with a curved bearing surface 40 contacting with a bearing surface 41 on the upper end of the sleeve 30^a. These surfaces are curved about an axis extending through the point "A" lengthwise of the knife and holder. The upper side of the adjusting or bearing block 38 is provided with a curved bearing surface 42 contacting with a similar curved bearing surface 43 on the lower end of the collar 39. These bearing surfaces 42 and 43 are curved about an axis extending through the point "A" at right angles to the other axis. Tongues or fingers 44 (Figs. 7 and 8) arranged in pairs on the bearing block 38 are guided in channels 45 or ways formed in the contacting bearing surfaces 41 and 43 for the pur- 13

pose of controlling the direction of movement of the bearing block and knife holder during adjustment thereof.

In adjusting the angular position of the knife and holder the locking screw 31 is loosened sufficiently to allow rocking of the holder by adjusting the set screws 36. The set screws are then adjusted, one pair at a time, until the cut-off knife assumes the desired angular position with respect to the blank molds, after which the locking screw 31 is tightened sufficiently to secure the knife holder and rock shaft against relative movement. After this adjustment the rock shaft 10 with the knife and holder, are lowered as described in connection with the first form of the present invention.

Because of the provision of a swivel connection or universal joint between the knife holder and rock shaft, it is evident that almost any necessary adjustment of the knife may be effected with very little difficulty.

Modifications may be resorted to within the spirit and scope of the appended claims.

25 What I claim is:

1. In combination, a blank mold having a charge receiving opening in one end, a cut-off knife adapted to sever gathered charges in the mold from a supply body, a rock shaft 30 supporting the knife, means for operating the rock shaft to thereby actuate the knife, means providing a ball and socket joint connecting the knife and rock shaft and permitting universal adjustment of the angular position of the knife with respect to the shaft and mold, and means for securing the knife in adjusted position.

2. Cut-off mechanism comprising in combination, a rock shaft, a knife holder, a knife 40 carried by the holder, and means providing a ball and socket joint connecting the holder and rock shaft and permitting universal angular adjustment of the knife and holder about a pivot point in the axis of the rock shaft.

3. Cut-off mechanism comprising in combination, a rock shaft, a knife holder, a knife carried by the holder, means providing a ball and socket joint connecting the holder and rock shaft and permitting universal angular adjustment of the knife and holder about a pivot point in the axis of the rock shaft, and means for adjusting said shaft in the direction of its length.

4. Cut-off mechanism comprising a knife, a holder therefor, a rock shaft adapted to support the knife and holder, means providing a swivel connection between the rock shaft 50 and knife holder comprising a crown portion on the holder, a cup carried by the shaft and adapted to be seated on said crown, and clamping means for securing the cup and crown portion in any adjusted position including a locking bolt extending through said

crown and screw threaded into said shaft.

5. Cut-off mechanism comprising a knife, a holder therefor, a rock shaft adapted to support the knife and holder, means providing a swivel connection between the rock shaft 70 and knife holder comprising a crown portion on the holder, a cup carried by the shaft and adapted to be seated on said crown, and clamping means for securing the cup and crown portion in any adjusted position, said 75 crown portion having an opening therethrough, said clamping means comprising a locking screw extending through said opening and threaded into the adjacent end of the rock shaft.

6. Cut-off mechanism comprising a rock shaft, a cut-off knife, a holder for the knife, said holder including a sleeve loosely fitted over one end of the rock shaft and universally adjustable angularly with respect to the axis 85 of said shaft, means for separably connecting the shaft and holder, and a series of set screws carried by the sleeve and engaging portions of the rock shaft, said screws adjustable to effect said universal adjustment of 90 said sleeve and thereby change the angular position of the holder and knife relative to the shaft.

7. Cut-off mechanism comprising a rock shaft, a cut-off knife, a holder for the knife, said holder including a sleeve loosely fitted over one end of the rock shaft, means separably connecting the shaft and holder, a collar fixed to the shaft above the sleeve, the adjacent ends of said sleeve and collar having bearing surfaces curved about relatively right angularly disposed axes, a bearing block 95 arranged between said sleeve and collar and having bearing surfaces contacting with those on the adjacent ends of the collar and sleeve, and means for angularly adjusting the holder 100 on the rock shaft, causing relative movement between the bearing block and adjacent bearing surfaces and a change in the angular position of the knife and holder with respect to the shaft.

8. Cut-off mechanism comprising a rock shaft, a cut-off knife, a holder for the knife, said holder including a sleeve loosely fitted over one end of the rock shaft, means separably connecting the shaft and holder, a collar fixed to the shaft above the sleeve, the adjacent ends of said sleeve and collar having bearing surfaces curved about relatively right angularly disposed axes, a bearing block 115 arranged between said sleeve and collar and having bearing surfaces contacting with those on the adjacent ends of the collar and sleeve, and means for angularly adjusting the holder on the rock shaft, causing relative movement between the bearing block and adjacent bearing surfaces and a change in the angular position of the knife and holder with respect to the shaft, said adjusting means comprising a series of set screws mounted in 120 125 130

the sleeve and having bearing contact at their inner ends with the rock shaft.

9. Cut-off mechanism comprising a rock shaft, a cut-off knife, a holder for the knife, 5 said holder including a sleeve loosely fitted over one end of the rock shaft, means separably connecting the shaft and holder, a collar fixed to the shaft above the sleeve, the adjacent ends of said sleeve and collar having 10 bearing surfaces curved about relatively right angularly disposed axes, a bearing block arranged between said sleeve and collar and having bearing surfaces contacting with those on the adjacent ends of the collar and 15 sleeve, means for angularly adjusting the holder on the rock shaft causing relative movement between the bearing block and adjacent bearing surfaces and a change in the angular position of the knife and holder with 20 respect to the shaft, and means for controlling the direction of movement of the bearing block during angular adjustment of the knife and holder.

Signed at Alton, Illinois, this 30th day of 25 August, 1930.
